UNITED STATES PATENT OFFICE.

WILLIAM MARIMAN WEBBER, OF GROVELAND, FLORIDA, ASSIGNOR OF ONE-FOURTH
TO HENRY W. SHEPPARD AND ONE-FOURTH TO GEORGE W. WOODS, BOTH OF
GROVELAND, FLORIDA.

AIRSHIP.

1,160,552. A device or device of the Specification of Letters Patent. Patented Nov. 16, 1915.

Application filed December 31, 1914, Serial No. 879,913.

To all whom it may concern:

Be it known that I, WILLIAM M. WEBBER, a citizen of the United States, residing at Groveland, in the county of Lake and State 5 of Florida, have invented certain new and useful Improvements in Airships, of which the following is a specification.

The present invention relates to certain new and useful improvements in airships, 10 and has for its object to provide a device of this character which embodies novel features of construction whereby it is always under the complete control of the aviator and is adapted to be used for commercial purposes 15 in transporting goods, passengers, etc., from place to place.

A further object of the invention is to provide an airship which combines a gas bag and supporting planes in such a manner as to obtain greater buoyancy, which has the propellers mounted in such a manner 20 that they can be quickly swung into various angular positions so as to either lift the machine straight up or drive it forward or backward, which can be quickly turned to the right or to the left by means of the propellers, and which can be guided in the usual manner by means of a rudder.

With these and other objects in view, the 30 invention consists in certain novel combinations and arrangements of the parts as will more fully appear as the description proceeds, the novel features thereof being pointed out in the appended claims.

For a full understanding of the invention, reference is to be had to the following description and accompanying drawing, in which:

Figure 1 is a side elevation of an airship 40 constructed in accordance with the invention. Fig. 2 is a rear end view of the same.

Fig. 3 is a plan view of the boat and propeller frames showing the gearing for driving the propellers, portions of the boat being 45 broken away. Fig. 4 is a detail sectional view through one of the propeller tubes, showing the gearing between the propeller shaft and the transverse drive shaft. Fig.

5 is a detail view of the gearing between the 50 engine and the transverse shaft. Figs. 6 and 7 are detail views of one of the propeller controlling levers. Fig. 8 is a detail perspective view of the rudder. Fig. 9 is a detail view of a portion of the rudder mecha-

nism, portions being broken away and shown in section.

Corresponding and like parts are referred to in the following description and indicated in all the views of the drawings by the same reference characters.

Referring to the drawings which illustrate one possible embodiment of the invention, the numeral 1 designates an elongated gas bag which extends longitudinally of the machine, and 2 supporting planes which project laterally from opposite sides of the gas bag, both the gas bag and supporting planes being mounted upon and held in proper relative position by means of a frame 3. Arranged below the gas bag 1 is a boat 4 which is suspended from the main frame 3 and connected to both the main frame and the supporting planes 2 by means of hangers and brace members 5. Projecting laterally from opposite sides of the boat 4 are suitable propeller frames 6 and extending transversely across the boat and frames 6 is a transverse drive shaft 7 which is journaled in suitable bearings 8. Power may be applied to the transverse drive shaft in any suitable manner from an engine 9 which is of the conventional construction and suitably mounted upon the boat 4. In the present instance the engine shaft 10 is connected by the bevel gearing 11 to a vertical shaft 12, said vertical shaft being in turn connected by the bevel gearing 13 to the transverse drive shaft 7. A conventional form of clutch 14 may be applied to the engine shaft to admit of the driving connection between the engine and the propellers being made or broken as desired.

A propeller 15 is provided upon each side of the machine and arranged within a propeller tube 16, said tubes serving to reduce the effect of end slip and also to prevent side currents of air from interfering with the proper action of the propellers, said tubes being slightly wider at the top than the bottom so as to be funnel shaped. Each of the propeller tubes 16 is mounted upon one of the propeller frames 6, being supported by a pair of hangers 17 which are loosely suspended from the transverse drive shaft 7. Extending transversely across the interior 105 of each of the propeller tubes 16 is a bar 18 upon which the propeller shaft 19 is journaled, said propeller shaft extending axially

through the propeller tube 16 and being connected to the transverse drive shaft 7 by means of bevel gearing 20. With this construction it will be obvious that the propeller tube 16 can be swung back and forth upon the transverse shaft 7 as a pivot center so as to be set in various angular positions without interfering in any manner with the operativeness of the driving connection between the propeller shaft 19 and the transverse driving shaft 7. When the propeller tube 16 is swung downwardly the force of the propeller will tend to lift the machine straight up into the air, while when the propeller tube is swung either to the rear or to the front the force of the propeller will tend to drive the machine forward or backward as the case may be.

The hangers 17 of each of the propeller tubes 16 are provided with the extensions 17^a which project upwardly above the transverse drive shaft 7. These extensions 17^a of the hangers are shown as connected to a yoke 21 at one end of an arm 22, the opposite end of the said arm being connected to a crank arm 23 upon a rock shaft 24 which is journaled within suitable bearings 25 at one end of the corresponding propeller supporting frame 6. A second crank arm 26 at the inner end of the rock shaft 24 is connected by a rearwardly extending link 27 to an operating lever 28, so that by suitably manipulating the operating lever the angular position of the propeller tube 16 can be adjusted so that the force of the propeller will act in the desired manner either to lift the machine straight up or to propel it to the front or rear.

One of the operating levers 28 is provided for the propeller upon each side of the machine and these operating levers are loose upon a transverse shaft 29 extending across the boat and journaled in suitable bearings 30. Each of the operating levers 28 is shown as provided with a conventional latch 31 for engaging a circular rack 32 rigid with the shaft 29. The two levers 28 are normally locked to the shaft 29 by means of the latches 31 and circular racks 32 so that when it is desired to swing both of the propellers and propeller tubes in the same direction and set the same at an identical angle, it is merely necessary to operate one of the levers. However, when it is desired to swing the propeller tubes 16 in opposite directions for the purpose of causing the machine to spin around quickly in mid-air, the two levers 28 are each grasped, the latches 31 thereon disengaged from the circular racks 32 and the levers swung in opposite directions. The propellers may thus either be swung in opposite directions and moved independently of each other, or both of them locked together so as to be moved in the same direction and set at the same angle

when either of the operating levers 28 is manipulated. Any suitable means such as the spring pawls 33 may be provided for holding the shaft 29 against rotation. The rudder 34 which is mounted at the rear of the boat may be of any conventional construction and is secured to a rudder post 35. In the present instance the rudder is shown as formed of four wings 34^a which are arranged at right angles to each other and radiate from the axis of the post 35, such a construction enabling the rudder to be used for guiding the machine up and down as well as laterally to the right and to the left.

The rudder supporting frame is mounted upon the rear end of the boat and includes a pair of spaced heads 36. The rudder post 35 projects loosely through an opening 37 in one of the heads 36, while the operating lever 38 projects loosely through a similar opening 39 in the opposite head. Both the rudder post 35 and the operating lever 38 are mounted to have a universal swinging movement so that they are free to swing in all directions, and suitable thrust joints are provided for preventing the members from being pulled longitudinally from the heads 36 of the rudder supporting frame. As indicated upon the drawing, a suitable thrust joint may be conveniently provided upon the rudder post 35 by placing an annular enlargement 40 thereon so that it will bear loosely against the inner face of the head 36. A similar annular enlargement 41 may be applied to the operating lever 38 so as to bear loosely against the inner face of the opposite head 36.

The inwardly projecting ends of the rudder post 35 and operating lever 38 are arranged in alignment with each other when the rudder is in normal position so as to cause the machine to move straight ahead, and these inwardly projecting ends are connected by a series of cables 42, said cables passing around suitable guide members such as the pulleys 43 applied to the opposite heads 36. The operation of these cables 42 is such that when the operating lever 38 is swung into an angular position the rudder post is simultaneously swung into a corresponding angular position. The aviator thus has the rudder under his complete control and can easily swing the rudder into any desired angular position for guiding the machine up and down or to the right and left, by suitably manipulating the operating lever 38. The lever 38 may be placed in a position adjacent the seat of the aviator so as to be readily grasped by him, while the rudder 34 may be mounted in the most effective position at the rear end of the airship.

The gearing between the vertical shaft 12 and the transverse drive shaft 7 includes a horizontally disposed gear wheel 50 applied

- to the upper end of the shaft 12 and meshing with corresponding bevel pinions 51 which are loose upon the shaft 7. With this construction it will be obvious that the two bevel gear wheels 51 revolve in opposite directions so that when the shaft 7 is locked with one of the gear wheels 51 the propellers will be driven in one direction, while when the said shaft is locked with the other gear wheel 51 the propellers will be driven in the opposite direction. A conventional form of clutch member 52 is mounted upon the shaft 7 between the gear wheels 51 and has a feather and spline connection with the shaft. 10 A shifting lever 53 is provided for moving the clutch member 52 back and forth and by moving the said clutch member into engagement with either one of the gear wheels 51 the shaft 7 can be locked with the said gear wheel so as to drive the propellers in a corresponding direction. When the propeller tubes 16 are swung downwardly, the propellers can be driven in one direction to lift the machine straight up into the air, 20 or driven in a reverse direction to pull the machine down to earth, thereby enabling a landing to be made without the necessity of letting out gas from the gas bag.
- The boat 4 is designed in such a manner 30 that it will float upon the water when desired and the same propellers which serve to move the machine through the air may also be utilized for moving the boat through the water. The hull of the boat is preferably constructed of the spaced shells 4^a, as indicated by Figs. 1 and 2 so as to provide a chamber between the same which can be filled with gas, hot air or the exhaust from the engine, in such a manner as to increase 40 the buoyancy of the boat.
- Having thus described the invention, what I claim as new and desire to secure by Letters Patent, is:—
1. An airship including a frame, a transverse drive shaft journaled thereon, propeller tubes, hangers supporting the propeller tubes and journaled upon the transverse drive shaft, a propeller mounted within each propeller tube and geared to the transverse 45 drive shaft, a lever for each propeller tube, an operative connection between each lever and the corresponding propeller tube for spinning the latter about the transverse drive shaft as an axis into various angular positions, a shaft upon which the two levers are mounted, latch means for locking the levers with the shaft, and means for normally holding the shaft against rotation.
  2. An airship including a frame, a transverse drive shaft journaled thereon, propeller tubes, hangers supporting the propeller tubes and journaled upon opposite ends of the drive shaft, a propeller mounted within each propeller tube and geared to the drive 60 shaft, a lever shaft, a pair of levers loose upon the shaft, an operative connection between each lever and the corresponding propeller tube for spinning the latter about the transverse drive shaft as an axis into various angular positions, a shaft upon which the two levers are mounted, latch means for locking the levers with the shaft, and means for normally holding the shaft against rotation.
  3. An airship including a frame, a transverse drive shaft journaled thereon, propeller tubes, hangers supporting the propeller tubes and journaled upon opposite ends of the transverse drive shaft, a propeller mounted within each propeller tube and geared to the transverse drive shaft, a lever shaft, a pair of levers loose upon the lever shaft, an operative connection between each lever and the corresponding propeller tube for spinning the latter about the transverse drive shaft as an axis into various angular positions, circular racks upon the metal shaft, latch members upon the levers for detachably engaging the circular racks, and spring detents engaging the circular racks to normally hold the lever shaft against rotation. 70
  4. An airship including a frame, a transverse drive shaft journaled thereon, propeller tubes, hangers supporting the propeller tubes and journaled upon opposite ends of the transverse drive shaft, a propeller mounted within each propeller tube and geared to the transverse drive shaft, a lever shaft, a pair of levers loosely mounted upon the lever shaft, an operative connection between each lever and the corresponding propeller tube for spinning the latter about the transverse drive shaft as an axis into various angular positions, circular racks upon the metal shaft, latch members upon the levers for detachably engaging the circular racks, and spring detents engaging the circular racks to normally hold the lever shaft against rotation. 80
  5. An airship including a frame, a transverse drive shaft journaled thereon, propeller tubes, hangers supporting the propeller tubes and journaled upon opposite ends of the transverse drive shaft, a propeller mounted within each propeller tube and geared to the transverse drive shaft, extensions projecting from the hangers, rock shafts provided with crank arms, an operative connection between the hanger extensions of each propeller tube and one of the crank arms of the corresponding rock shaft, a controlling lever for each of the propeller tubes, an operative connection between each of the controlling levers and the other crank arm of the corresponding rock shaft, and means for locking the levers together so that they can be moved in unison. 95
  6. An airship including a frame, a transverse drive shaft journaled thereon, propeller tubes, hangers supporting the propeller tubes and journaled upon the transverse drive shaft, a propeller mounted within each of the propeller tubes and geared to the transverse drive shaft, extensions projecting from the hangers, a pair of rock shafts each of which is provided with a pair of crank arms, a yoke member connecting the hanger extensions of each of the propeller tubes to one of the crank arms of the corresponding rock shaft, a lever shaft, a pair of levers loose upon the lever shaft, a link member connecting each lever to the opposite crank arm of the corresponding rock shaft, circular racks upon the lever shaft, latch means upon the levers for engaging the circular racks, and means for normally holding the lever shaft against rotation. 100
  7. An airship including a frame, a transverse drive shaft journaled thereon, propeller tubes, hangers supporting the propeller tubes and journaled upon the transverse drive shaft, a propeller mounted within each of the propeller tubes and geared to the transverse drive shaft, extensions projecting from the hangers, a pair of rock shafts each of which is provided with a pair of crank arms, a yoke member connecting the hanger extensions of each of the propeller tubes to one of the crank arms of the corresponding rock shaft, a lever shaft, a pair of levers loose upon the lever shaft, a link member connecting each lever to the opposite crank arm of the corresponding rock shaft, circular racks upon the lever shaft, latch means upon the levers for engaging the circular racks, and means for normally holding the lever shaft against rotation. 105
  8. An airship including a frame, a transverse drive shaft journaled thereon, propeller tubes, hangers supporting the propeller tubes and journaled upon the transverse drive shaft, a propeller mounted within each of the propeller tubes and geared to the transverse drive shaft, extensions projecting from the hangers, a pair of rock shafts each of which is provided with a pair of crank arms, a yoke member connecting the hanger extensions of each of the propeller tubes to one of the crank arms of the corresponding rock shaft, a lever shaft, a pair of levers loose upon the lever shaft, a link member connecting each lever to the opposite crank arm of the corresponding rock shaft, circular racks upon the lever shaft, latch means upon the levers for engaging the circular racks, and means for normally holding the lever shaft against rotation. 110
  9. An airship including a frame, a transverse drive shaft journaled thereon, propeller tubes, hangers supporting the propeller tubes and journaled upon the transverse drive shaft, a propeller mounted within each of the propeller tubes and geared to the transverse drive shaft, extensions projecting from the hangers, a pair of rock shafts each of which is provided with a pair of crank arms, a yoke member connecting the hanger extensions of each of the propeller tubes to one of the crank arms of the corresponding rock shaft, a lever shaft, a pair of levers loose upon the lever shaft, a link member connecting each lever to the opposite crank arm of the corresponding rock shaft, circular racks upon the lever shaft, latch means upon the levers for engaging the circular racks, and means for normally holding the lever shaft against rotation. 115
  10. An airship including a frame, a transverse drive shaft journaled thereon, propeller tubes, hangers supporting the propeller tubes and journaled upon the transverse drive shaft, a propeller mounted within each of the propeller tubes and geared to the transverse drive shaft, extensions projecting from the hangers, a pair of rock shafts each of which is provided with a pair of crank arms, a yoke member connecting the hanger extensions of each of the propeller tubes to one of the crank arms of the corresponding rock shaft, a lever shaft, a pair of levers loose upon the lever shaft, a link member connecting each lever to the opposite crank arm of the corresponding rock shaft, circular racks upon the lever shaft, latch means upon the levers for engaging the circular racks, and means for normally holding the lever shaft against rotation. 120
  11. An airship including a frame, a transverse drive shaft journaled thereon, propeller tubes, hangers supporting the propeller tubes and journaled upon the transverse drive shaft, a propeller mounted within each of the propeller tubes and geared to the transverse drive shaft, extensions projecting from the hangers, a pair of rock shafts each of which is provided with a pair of crank arms, a yoke member connecting the hanger extensions of each of the propeller tubes to one of the crank arms of the corresponding rock shaft, a lever shaft, a pair of levers loose upon the lever shaft, a link member connecting each lever to the opposite crank arm of the corresponding rock shaft, circular racks upon the lever shaft, latch means upon the levers for engaging the circular racks, and means for normally holding the lever shaft against rotation. 125
  12. An airship including a frame, a transverse drive shaft journaled thereon, propeller tubes, hangers supporting the propeller tubes and journaled upon the transverse drive shaft, a propeller mounted within each of the propeller tubes and geared to the transverse drive shaft, extensions projecting from the hangers, a pair of rock shafts each of which is provided with a pair of crank arms, a yoke member connecting the hanger extensions of each of the propeller tubes to one of the crank arms of the corresponding rock shaft, a lever shaft, a pair of levers loose upon the lever shaft, a link member connecting each lever to the opposite crank arm of the corresponding rock shaft, circular racks upon the lever shaft, latch means upon the levers for engaging the circular racks, and means for normally holding the lever shaft against rotation. 130

shaft journaled thereon and extending transversely across the same, propeller members supported by opposite ends thereof and driven thereby, a pair of bevel gears loose upon the transverse shaft at an intermediate point in the length thereof, a vertical shaft, a bevel gear wheel applied to the vertical shaft and meshing with the pair of bevel gears loose upon the transverse shaft, means for applying power to the vertical shaft, and a clutch member arranged upon the transverse shaft between the pair of gear wheels and having a feather and spline con-

nexion with the shaft, said clutch member being adapted to be moved into engagement 15 with either one of the pair of gear wheels to lock the shaft therewith and the direction of rotation of the shaft, depending upon which one of the gear wheels is locked therewith.

In testimony whereof I affix my signature 20 in presence of two witnesses.
